BOTTLE CLOSURE CAP RELEASING MEANS AND CAPS ASSOCIATED THEREWITH

Edwin Ralph Rossiter, Sydney, New South Wales,
Australia

Application March 29, 1933, Serial No. 663,412
In Australia April 19, 1932

3 Claims. (Cl. 215—46)

This invention refers to improvements in and connected with bottle closure cap releasing means and caps associated therewith.

The invention has particular reference to and is particularly associated with bottle sealing devices of the type comprised by metal caps each provided with a cork insert piece and generally known as a "crown cork". Such "crown corks" for purposes of the application of the invention have their top faces sunken or indented as will be seen.

Numerous devices have been made and employed for the purpose of facilitating the removal of caps or "capsules" of the "crown cork" variety. Such known means include separate specially formed tools or appliances the use of which frequently results in damage to the bottle neck, while furthermore inconvenience is obviously caused if the tool be not handy for use.

Other such known means comprise the provision of an integral tag portion to each such cap, but the general use of such has hitherto been impossible in keeping with modern rapid methods of sealing bottles without necessitating also the use of special machinery designed to take the place of existing machinery and so to ensure rapid assembly and feeding of the caps when required for bottle sealing purposes, and bottlers are naturally disinclined to install such special machinery.

The present invention contemplates the provision of simple improved means cheaply applied and incorporated with or as an integral part of each said cap and utilizable (subsequently to sealing of a bottle with the cap) for release of the latter as by means of a pull or leverage exerted and capable of being applied through the medium of a handkerchief or a shoe lace, or a pencil, penknife, paper knife, spoon handle or other like handy appliance which is adapted to function as the necessary pulling element or lifting lever.

The closure according to the invention has the advantage that it may be handled with a maximum of ease and rapidity by existing known automatic bottle sealing mechanisms.

The invention consists in a bottle closure cap of the kind having releasing means associated with a bottle closure cap comprising a substantially loop-like formation of wire or like suitable material whose two extremities are engaged beneath the gofferings and a cork or like insert piece of the closure cap, in which the two extremities lie along exterior grooves of the closure cap

gofferings and are then inturned to lie along interior grooves of the said gofferings.

If desired, the two extremities may be engaged between the cork insert piece and the metal cap, or between the cork insert piece and an intermediate lining as of paper located between cork and cap or between paper and cap.

Closure caps associated with releasing means contemplated by the invention are sunken or indented as in conformity with the configuration of the said releasing means which latter are designed to be bent and snugly received by and nested in the said sunken or indented cap upon its upper surface and so that the said releasing means may in no way obtrude or interfere with the free passage of the cap (with releasing means fitted or incorporated) along the feed chute and directly into the throat or mouth of and into an automatic "crown cork" bottle sealing mechanism of character commonly in use.

But in order that the invention may be more readily understood reference will now be made to the accompanying drawing wherein like reference numerals denote like parts throughout the several views which are as follow:

Figure 1 is a perspective view of one known design of metal closure cap before being formed and fitted according to the invention with associated releasing means.

Figure 2 is a perspective view of the said design of closure cap after it has been formed or indented but before it has been fitted with associated releasing means according to the invention.

Figure 3 is a cross sectional view taken on the line A—B of Figure 2.

Figure 4 is a perspective view of the said design of closure cap formed and fitted according to the invention with associated releasing means of wire.

Figure 5 is a cross sectional view taken on the line C—D of Figure 4.

Figure 6 is an inverted perspective view of the closure cap formed and fitted as illustrated by Figure 4, the cork or paper insert having been removed.

Figure 7 is a cross sectional view taken on the line E—F of Figure 4, but showing usual cork insert piece and an intermediate lining fitted in position.

Figure 8 is a perspective view of the wire fitting (detached from the closure cap) as illustrated by Figure 6.

Figure 9 is a cross sectional view taken on the line H—I of the wire fitting indicated by Figure 8.

Figure 10 is a view of the said closure cap

functioning to seal a bottle mouth, associated releasing means being fitted according to the invention, the raised position of the said releasing means (in dotted lines) being approximately that 5 which is occupied by the same when the cap is about to be removed from the bottle mouth.

It will of course be understood that although the drawing herein illustrates preferred constructions according to the invention the latter 10 in its application may be varied in regard to details without departing from its scope and spirit as herein defined.

The metal cap 13 has sunken portions or indentations 14 and 14a and upstanding portions or 15 ridges 15 with grooves at 16 permitting portions of the wire loop 17 to lie snugly within them and be nested within the sunken portion or indentation 14 and preferably slightly below ridges 15 so that the wire loop 17 may not protrude itself 20 beyond the uppermost face of the cap.

The inner faces of the said sunken portions or indentations 14 and 14a are in the same plane and together adapted to form convenient bearing faces against which is fitted the paper or like lining 26a against which in turn is the cork insert 25 piece 26 according to known practice.

Portions of the loop 17 are bent at 18 to lie along exterior grooves formed by the gofferings and are then inturned to lie along interior 30 grooves 20 of said gofferings and their ends 21 then each take an approximately right-angled turn away from each other to be snugly accommodated within the portion of the interior recess 22 of a ridge 15.

35 By this arrangement it will be observed that no portions of the wire forming the bends 23 lie in superimposed relationship (see Figure 9) and thus do not militate against subsequent desirable neat fitting of a cork insert piece 26 and an intermediate lining 26a as of paper (see Figure 7); and further that the wire ends are adapted to afford ample bearing surface with the inner face of the cap interior recess 22 when the wire loop 17 has applied to it a handkerchief or the like 40 24 or a lever 25 to effect release of the cap 13 from a bottle neck to which it has been fitted.

It may be here noted as important that during the normal act of sealing a bottle mouth with a closure cap of the "crown cork" type the goffering or crimped skirt portion of the latter is 50 pressed inwardly, and when so applying according to the present invention a closure cap and its associated cap releasing means the said inward pressure causes the said releasing means to be slightly raised away from the sunken cap surface or indentation 14 so to be in ready position for insertion of a handkerchief or the like 55 24 or lever 25 (see Figure 10 of the drawing).

60

65

70

75

If desired, an approved portion of the ridge 15 disposed say approximately diametrically opposite the wire loop 17 may be formed with a series of grooves or serrations (not shown in the drawing herein) whose function is to afford a convenient grip to any levering device employed in the manner and for the purpose described and illustrated.

Ends 21 of the wire loop 17 may be somewhat flattened out should this be deemed desirable to 85 obviate wear upon the cork insert piece 26 or upon the paper of like lining 26a.

By the use of the invention while there is secured a maximum of sealing efficiency, damage by chipping of bottle necks due to removal of the 90 closure caps therefrom is entirely eliminated; and bottle closure caps are associated with releasing means for each of the same in manner so that the composite article so formed may be quite conveniently handled by the same automatic bottle 95 sealing mechanisms which are at present in use for handling crown seal bottle closures of known conventional type.

Within the spirit of the invention as described and claimed herein, there may be employed modifications in regard to shape, design and disposition of cap indentations or cap releasing means.

What I claim is:—

1. A goffered bottle cap having a partially peripheral groove on its undersurface forming a 105 ridge on the upper surface with a re-entrant angle and a loop formation of wire the curved extremities of which lie within the peripheral groove, pass along an interior goffering groove over the edge of the cap and along an exterior 110 goffering groove the loop of the wire lying within a recess defined by the re-entrant portion of the ridge.

2. A goffered bottle cap closure having an interrupted circumferential ridge on the top surface 115 and a re-entrant angle, with corresponding grooves on the under surface, the interruption being at least one indentation in the circumferential ridge at the opening of the re-entrant angle, and a looped releasing wire, the loop of which 120 lies within the re-entrant angle and at least one branch passes to the under surface through the said indentation and along the exterior and interior goffering grooves.

3. A goffered bottle cap closure, a partial peripheral groove with a re-entrant angle on its under surface and a corresponding ridge on its upper surface, an arc shaped ridge separated by indentations from the peripheral ridge and a loop 125 formed release wire lying within the recesses 130 formed by said ridges and by said goffering.

EDWIN RALPH ROSSITER.
